TUYÈRE CONSTRUCTION FOR CUPOLAS

Joshua K. Clutts, Detroit, Mich.

Application January 7, 1935, Serial No. 695

4 Claims. (Cl. 266—41)

This invention relates to tuyères, and particularly cupola tuyères.

It is well known that the tuyères of a cupola at times become more or less clogged with slag or molten metal, so as to prevent adequate admission of air and detract from the quality of the melt. Occasionally, also, one or more of the tuyères are melted away to an extent necessitating a replacement. In present practice, the tuyères are permanently embedded in the fire brick lining of a cupola and it is not feasible to clean out the tuyères until the melt has been run and the cupola has cooled. It follows that any material clogging of the tuyères in the course of a heat necessitates either inferior castings during the balance of the heat, or pigging of the melt, usually with great loss of time and fuel.

An object of the invention is to adapt the primary tuyères of a cupola for ready removal, so that any clogged tuyère may at once be replaced by a fully operative tuyère without interfering with operation of the cupola except as regards cutting off the air for a short time interval.

Another object is to permit a quick and easy replacement of a burned-out tuyère, whether or not the cupola is in operation, and to avoid the destruction of fire brick involved in replacing the present type of built-in tuyères.

A further object is to form the air passage of a cupola tuyère with an outward flare rather than an inward one as in present practice, so that the velocity of the air in passing through the tuyère will increase rather than diminish, whereby the air will more readily penetrate the contents of the cupola and will have less tendency to rise in close proximity to the lining. Thorough penetration of the contents of the cupola by incoming air is essential to proper preservation of the lining, as any undue rise of air in proximity to the lining generates undue heat in such proximity, with a destructive effect on the lining.

A further object is to form in a suitable frame one or more compartments, in each of which a cupola tuyère may be removably inserted, and to adapt the size of such compartment or compartments to be varied to properly accommodate tuyères of different sizes.

These and various other objects the invention attains in the construction hereinafter described, and illustrated in the accompanying drawings, wherein:

Fig. 1 is a view in axial sectional elevation of the melting zone and basin of a cupola in which the improved tuyères are installed.

Fig. 2 is a cross sectional view of the same,

taken upon the line 2—2 of Fig. 1 and showing the main tuyères.

Fig. 3 is an enlarged view of the inner end of one of the tuyère frames of the main tuyères.

Fig. 4 is a horizontal sectional view taken upon the line 4—4 of Fig. 3.

Fig. 5 is a perspective view of a wall plate, forming a removable part of the tuyère frame shown in Figs. 3 and 4.

Fig. 6 is a horizontal section taken on the line 6—6 of Fig. 1 and showing the auxiliary tuyères.

In these views, the reference character 1 designates a cupola having the usual fire brick lining 2 and surrounding wind box 3, the latter having the usual air inlet.

Built into the lining 2 is a circular series of rectangular tuyère frames 4, formed preferably of cast iron. Each of these frames forms a plurality of circumferentially spaced tuyère compartments 5, two being shown, and preferably there is formed a space 6 between such compartments with a cross wall 6a therein connecting the adjacent walls of the compartments. The compartments extend from the outer to the inner faces of the frames, which faces are preferably flush with the inner and outer faces of the fire brick lining. In each compartment 5 is removably inserted a primary tuyère 7 forming an air passage through the frame 4 and through the cupola wall. The side walls of the frames 4 and tuyères 7 converge as they extend inwardly, so that the air passages are outwardly flaring, and preferably the convergent relation of said walls is established by forming said walls substantially radially to the axis of the cupola, as best appears in Fig. 2.

In prior cupolas, the tuyère capacity is substantially fixed, restricting the cupola to use of a certain type of fuel to which such capacity is suited. The present invention adapts a cupola to use of different types of fuel by providing for selective insertion in the frames 4 of tuyères of various sizes. Thus, as best appears in Figs. 3 and 4, the top and bottom plates of each tuyère frame are formed with several pairs of opposed grooves 8, and a wall plate 9 is removably inserted in each pair of such grooves. Thus, by removal of one or more of the plates 9, the width of each compartment may be increased to adapt such compartment to receive a tuyère of greater air capacity. It is preferred to form each wall plate 9 with a vertical rib 9a to engage either the end wall of the tuyère frame or an adjacent plate 9, closing the spaces between the plates and between the latter and end walls of the frame and limiting inward sliding travel of the plates, owing

to the inwardly convergent relation of the grooves 8 and of said end walls.

The several tuyère frames 4 are spaced by portions 10 of the fire brick lining, which portions 5 preferably have a considerably less circumferential extent than the frames.

At a suitable level above the primary tuyères there is permanently built into the lining 2 a circular series of auxiliary tuyères 11. These are 10 considerably smaller than the primary tuyères and deliver correspondingly smaller volumes of air, but at a greater velocity than the blast from the primary tuyères. It is preferred to locate each auxiliary tuyère centrally above one of the 15 wall portions 10, so as to deliver the blast from the auxiliary tuyères to interior regions of the cupola, circumferentially intervening between those supplied by the primary tuyères. Thus, the two sets of tuyères jointly effect an air delivery 20 circumferentially covering the entire melting zone of the cupola.

To give access to the primary tuyères and permit of their individual removal and replacement, it is preferred to form the wind box with a series 25 of openings 12 in a radially opposed relation to the tuyère frames 4, so that the tuyères occupying each frame may be removed or replaced through one of said openings. The openings 12 are normally closed by doors 13, held in place by 30 any suitable fastening means 14.

At the usual points below the primary tuyères, are provided the usual slag hole 15, tap hole 16, and sand bottom 17.

In operation of the described cupola, when any 35 of the primary tuyères becomes clogged with slag or iron, or is unduly damaged by heat, removal and replacement of such tuyère may be quickly and easily accomplished by merely cutting off the air supply for a sufficient time interval to permit uncovering one of the openings 12, withdrawal 40 of the defective tuyère, and insertion of an operative one. If the tuyère so removed is obstructed with slag or iron, removal of the obstruction may be accomplished at leisure, and 45 the tuyère may be later placed in service.

By progressively restricting the air passages of the primary tuyères as they extend inwardly, the invention tends not only to assure thorough and uniform penetration of the stock by the air, but 50 further tends to avoid undue rise of the melting zone and consequent well known disadvantages. It has been found in actual practice that the described tuyères materially reduce the requisite quantity of fuel and improve the quality and uniformity of the melt.

In addition to the time saved in thus replacing a tuyère, the invention eliminates loss due to inferior iron due to clogging of any tuyère, and

further eliminates the destruction of fire brick, incident to removal and replacement of tuyères as now installed.

The invention is presented as including all such modifications and changes as come within the 5 scope of the following claims.

What I claim is:

1. In a tuyère construction for cupolas, a tuyère frame comprising top and bottom plates, spaced to form a tuyère compartment, a side wall 10 for such compartment extending between the top and bottom plates, and a plurality of plates insertable in a desired number, between the top and bottom plates, in different spaced relations to said side wall; and in a side-by-side relation, 15 the top and bottom plates each having a plurality of converging grooves to accommodate the inserted plates, each of the plates being laterally formed with a rib to engage the side of an adjoining plate and close the spaces between the 20 plates, whereby the number of such plates inserted regulates the size of the compartment.

2. A tuyère construction for cupolas, comprising spaced top and bottom plates, each having two spaced sets of converging grooves, vertically opposed on the top and bottom plates, a partition connecting the top and bottom plates, substantially midway between the two sets of grooves, and two sets of wall plates for insertion in the spaced sets of grooves in a side-by-side relation, 25 each wall plate being laterally formed with a rib to engage the side of an adjoining plate of the same set and close the space between the adjoining plates, whereby the number of plates inserted regulates the size of the compartments. 30

3. A tuyère frame having a fixed wall and having a plurality of removable walls differentially spaced from the fixed wall, a tuyère chamber being formed between the fixed wall and the group 35 of removable walls, and the size of such chamber being variable by removal of one or more of the removable walls.

4. A tuyère construction comprising top and bottom plates spaced to form a tuyère compartment, a side wall for such compartment extending between the top and bottom plates, and a plurality of plates insertable in a desired number between the top and bottom plates and in a side-by-side relation, the top and bottom plates each 40 having a plurality of converging grooves to accommodate the inserted plates, the adjoining plates interengaging in their inserted positions, due to convergence of said grooves to eliminate 45 spaces between the adjoining plates, whereby the number of inserted plates regulates the size of said compartment.

JOSHUA K. CLUTTS.
